UNITED STATES PATENT OFFICE

EXILIAS PAQUETTE, OF LOWELL, MASSACHUSETTS, ASSIGNOR TO LAWRENCE MANUFACTURING COMPANY, OF LOWELL, MASSACHUSETTS, A CORPORATION OF MASSACHUSETTS.

CIRCULAR-KNITTING MACHINE.

985,928.

Specification of Letters Patent. Patented Mar. 7, 1911.

Application filed April 5, 1909. Serial No. 487,876.

To all whom it may concern:

Be it known that I, EXILIAS PAQUETTE, a citizen of the United States, residing at Lowell, in the county of Middlesex and State of Massachusetts, have invented certain new and useful Improvements in Circular-Knitting Machines; and I do hereby declare the following to be a full, clear, and exact description of the invention, such as will enable others skilled in the art to which it appertains to make and use the same.

The invention relates to that class of circular knitting machines in which the needles are mounted in a needle cylinder and are operated upon by cams and controlling devices arranged about the cylinder, the relative movements between the needle and the needle operating cams and devices requisite for knitting a tubular fabric provided at intervals with heel and toe pockets, being produced by rotary and reciprocatory movements of either the needle cylinder or the support or cylinder on which the needle operating cams and controlling devices are mounted.

The object of the invention is to provide an improved and simplified construction and arrangement of needle operating cams and devices for knitting "split foot" stockings upon the above type of circular knitting machines.

The invention is intended primarily as an improvement on the construction of machine shown and described in patent No. 928,165, July 13, 1909, although it will be understood that the invention is not limited in its application to this construction of machine, and that the features of the invention may be embodied in other constructions and other forms of circular knitting machines for producing seamless hosiery.

The invention consists in the features and combinations hereinafter described and as defined in the claims.

The various features of the invention will be understood from an inspection of the accompanying drawings.

In these drawings Figure 1 is an elevation showing so much of a knitting machine as is necessary for an understanding of the features of the present invention; Fig. 2 is a

detail plan view of certain parts to be hereinafter described; Fig. 3 is a plan view with the cam cylinder and needle cylinder removed; Fig. 4 is a plan view of the cam cylinder; Fig. 5 is a sectional view on line 5—5, Fig. 4; Fig. 6 is a detail plan view of the picker shown in Fig. 5; Fig. 6 is a detail plan view of the picker shown in Fig. 5; Fig. 7 is an elevation showing a development of the inside of the cam cylinder; Fig. 8 is a perspective detail view showing the construction of the picker shown in Fig. 5; Fig. 9 is a diagrammatic view showing the arrangement of the long and short butt needles; Fig. 10 is a detail plan view of the shifter ring; Fig. 11 is a detailed elevation of the cam post for controlling the operation of the depressing pickers; Fig. 12 is a detailed elevation of certain parts to be hereinafter described; and Figs. 13 and 14 are details of the thread guiding devices for the supplemental cams.

In the drawings the various features of the invention are illustrated as embodied in a circular knitting machine having many of its parts constructed and arranged in the manner in which the corresponding parts are constructed and arranged in the machine which is illustrated in the patents to Mayo, No. 474,861, May 10, 1892, and No. 746,449, December 1, 1903, which will for convenience be referred to as the Mayo machine. In this machine the needles are carried in a needle cylinder, and are operated and controlled during the knitting by cams carried by a cam cylinder, which is either rotated or reciprocated, according to the part of the fabric or stocking which is being produced. In embodying the present improvements in this machine, I have retained the general construction and arrangement of the operating and controlling devices and have combined therewith certain additional needle operating and controlling devices, so that the mode of operation of the machine is changed and a different product is produced. In illustrating the invention, I have shown only so much of the machine as is necessary to an understanding of the features constituting the present invention, it being understood that the motion changing

mechanism, and the construction and mode of operation of the pattern mechanism for controlling the movements of various parts of the machine, are in general the same as in the Mayo machine. In the present machine, however, the devices for controlling the change of motion from rotary to reciprocating, and vice versa, are so constructed that the cam cylinder is reciprocated during the knitting of the foot of the stocking as well as during the formation of the heel and toe. This may be accomplished by devices operating to disconnect the clutch shifting lever from the clutch shifting yoke, as fully described in the patent above referred to.

In the machine shown the needle cylinder is the same in construction as the needle cylinder in the Mayo machine, and is supported in the same manner. The needles are divided into two substantially semicircular groups or series, one group, which is inactive during the knitting of the heel and toe, being provided with long butts, and the other group, which is active during the knitting of the heel and toe as well as during the knitting of the other parts of the stocking, being provided with short butts. Between the two long butt needles at each end of the series of long butt needles L (Fig. 9), short butt needles s s' are interposed, and these needles, together with the needles l l' of the long butt series, comprise the suture needles for connecting the fabrics knit upon the two groups of needles in knitting the split foot 35 of a stocking.

The cam cylinder is provided with devices for throwing the long butt needles out of action during the knitting of the heel and toe, and with needle elevating and needle depressing pickers for effecting the narrowing and widening during the knitting of the heel and toe, which are similar in construction and mode of operation to the corresponding devices in the Mayo machine, and is also provided with two sets of knitting cams and devices coöperating therewith during the knitting of the foot of the stocking to direct the short butt needles through one set of knitting cams, and to direct the long 50 butt needles through the other set of knitting cams and out of the path of the cams which act on the short butt needles, which are similar in general construction and mode of operation to the corresponding two sets 55 of knitting cams and coöperating devices shown and described in the prior application above referred to. The second set of knitting cams which act upon the long butt needles during the knitting of the split foot are 60 so constructed and controlled that they act upon all the needles during rotary knitting, although such construction and arrangement is not essential to certain features of the invention.

As shown in Fig. 7, the knitting cams 65 which act upon all the needles during rotary knitting, and upon the short butt needles during the knitting of the heel, toe and foot, and which may for convenience be termed the main knitting cams, comprise the two 70 stitch cams 2 and 3, the center switch cam 4, and the two elevating cams 5 and 6. The knitting cams which act upon all the needles during rotary knitting, and upon the long butt needles during the knitting 75 of the split foot, and which may for convenience be termed supplemental knitting cams, comprise the two stitch cams 7 and 8, the center switch cam 9, and the two elevating cams 10 and 11. The two center 80 switch cams 4 and 9 are pivotally mounted upon vertically adjustable slides 12 and 13, and are similar in construction to the center switch cam of the Mayo machine. The elevating pickers 14 and 15 and their controlling latches are similar in construction to the pickers and latches of the Mayo machine, and the throwing of these pickers into and out of action is controlled by a cam post 16 as in the Mayo machine. The 85 depressing pickers 17 and 18, and their latches 19 and 20, are similar in construction to the depressing pickers and latches of the Mayo machine, and the throwing of these pickers into and out of action is controlled 90 by a cam post 21 similar to the cam post for controlling the action of the depressing pickers in the Mayo machine. The cam 22 for raising the long butt needles into the upper or inactive plane at the beginning of 100 reciprocatory knitting, and for returning all the needles which are in the upper or inactive plane at the end of reciprocatory knitting to the active plane, is the same in construction and arrangement as the corresponding cam in the Mayo machine. This cam is mounted upon a rock shaft 23 supported in the cam cylinder, and provided at its outer end with a pinion 24 which is engaged by a rack on the side of a vertically 105 movable slide 25. The slide 25 is raised and lowered at the proper times by two cam arms 26 arranged to be moved alternately into position to operate upon a pin 27 which projects radially from the slide.

In order that the supplemental knitting cams may operate upon all the needles during rotary knitting, and may operate upon only the long butt needles during the knitting of the split foot, the center switch cam 9 is arranged to be moved radially inward so as to engage the butts of all the needles, or to be moved radially outward to a position where it will engage only the butts of the long butt needles. The inward and outward movements are imparted to the switch cam 9 at proper intervals by means of a bell crank lever 28, one end of which is connected 115

by a link 29 with a crank pin 30 carried by the shaft 23, and the other end of which engages a slot formed in the cylindrical shank of the switch cam (Figs. 4 and 7).

5 The devices for directing the long butt needles through the supplemental knitting cams, and out of the path of the main knitting cams during the continuance of the reciprocatory knitting, after the completion 10 of the heel or toe, as the case may be, comprise the needle elevating cam 22, a needle elevating cam 31 arranged on the opposite side of the knitting cams, and two needle depressing cams 32 and 33 arranged on opposite sides of the knitting cams and adapted 15 to engage both long and short butt needles. During the reciprocating of the cam cylinder in one direction, the cam 22 acts to raise the long butt needles into the inactive plane after 20 they have passed under the knitting cam 8 and up the elevating cam 11, and during the return stroke the butts of all the needles in the inactive series engage the cam 32 and are directed down into the active plane by 25 this cam and the inclined end of the guard cam 34. These long butt needles engage the switch cam 9, and are directed into the path of the stitch cam 7. After passing the stitch cam 7, the butts of the long needles 30 pass up the elevating cam 10 and up the cam 31 into the inactive plane. When the motion of the cam cylinder is reversed, the butts of the needles in the inactive series engage the depressing cam 33 and are directed by this 35 cam and the inclined end of the guard cam 35 down into the active plane. The butts of the long butt needles engage the switch cam 9 and are directed into the path of the stitch cam 8, passing down this cam and up 40 the elevating cam 11 and the elevating cam 22 into the upper or inactive plane. During reciprocatory knitting the switch cam 9 is withdrawn into position where it will not engage the short butt needles, and the elevating cams 22 and 31 are of such thickness 45 that they will not engage the short butt needles. The short butt needles therefore pass idly by the stitch cams 7 and 8, and are operated by the stitch cams 2 and 3.

50 During the knitting of the heel and toe the needle depressing cams 32 and 33 are moved downward so that they will be out of the path of the butts of the needles in the upper or inactive plane, and are still out of 55 the path of the butts of the needles in the lower or active plane and are returned into their upper active position at the completion of the heel and toe. The devices for thus operating the needle depressing cams 60 comprise two bell crank levers 36 and 37, provided at one end with slots engaging pins projecting radially from the slides 38 and 39 on which the cams are mounted. The other ends of the bell crank levers are con-

nected by links 40 and 41 with the opposite 65 ends of an arm 42 which is secured to a rock shaft 43. An arm 44 is secured to the outer end of the rock shaft 43, and is provided with a radially projecting pin 45 arranged to engage and be operated by a cam 70 arm 46 (Figs. 1 and 3). The cam arm 46 is secured upon a rock shaft 47 which is mounted in the fixed standard 48, and is provided at its outer end with an arm 49. The arm 49 is held in engagement with the 75 upper end of a vertically movable rod 50 by a spring 51. The lower end of the rod 51 is arranged to be engaged and operated by a cam block 52 carried by one end of a bell crank lever 53 which is secured to a rock 80 shaft 54. The other end of the bell crank lever is connected by a link 55 with the rear end of a lever 56. This lever corresponds to the lever of the Mayo machine which is connected with the clutch shifting lever and 85 operates to raise and lower the needle cylinder to vary the length of the stitches on the heel and toe. When the high part of the cam block 52 is in position under the end of the rod 50, the cam arm 46 is held in 90 the position indicated in the drawings, so that it will act when engaged by the pin 45 to rock the shaft 43 into the position indicated in the drawings, thus raising the needle depressing cams 32 and 33 into active 95 position as indicated in the drawings. When the high part of the cam block 52 is moved from under the rod 50, the cam arm 46 will be swung up into position to be engaged by the pin 45, and to shift the pin 100 downward, thus rocking the shaft 43 and moving the needle depressing cams 32 and 33 down into inactive position out of the path of the needle butts of the upper or inactive series of needles.

105 The needle elevating cam 31 is secured on the inner end of a shaft 57 which is mounted in the cam cylinder and is acted upon by a torsional spring 56 which tends to hold the cam in its active position, as indicated in Fig. 7. During rotary knitting the butts of the long butt needles pass under the cam 31 in a direction from left to right in Fig. 7, and the cam yields to allow the passage of the needle butts and rides idly along the 110 tops of the needle butts until the long butt needles have passed, and then automatically returns to active position. The cam therefore remains in active position when the long butt needles are thrown up into the inactive plane at the beginning of the heel or toe, and stands ready to raise the long butt needles out of the path of the main knitting cams when the long butt needles are directed through the supplemental knitting cams in 115 knitting a split foot.

120 It is important, for reasons which will be more fully explained hereafter, that neither

of the short butt suture needles should operate to knit during the first reverse stroke of the needle cylinder in going upon the heel, in case the heel is knit before the foot, 5 or in going upon the toe, in case the toe is knit before knitting the foot. For convenience it will be assumed in further explanation of the operation of the machine that it is arranged to first knit the leg of the stocking, and to knit the foot after the heel has 10 been completed. In the construction shown, the needle elevating pickers continue in operation during the knitting of the foot as well as during the narrowing and widening 15 in knitting the heel and toe. During the first reverse movement of the needle cylinder, therefore, in passing from the leg to the heel, the suture needle s will be lifted into the inactive plane by the lifting picker 20 15 before it reaches the knitting cams, so that this needle will not knit during this stroke of the needle cylinder. The means which are provided for raising the suture needle s' in to the inactive series, so that this 25 needle shall not knit during the first reverse stroke of the cam cylinder in going on to the heel, consists of a novel form of picker constructed to be operated by a long butt needle, and means for moving a long 30 butt needle from the upper or inactive series down into position to actuate the picker. In the construction shown, the depressing picker 18 is so controlled that when the motion of the needle cylinder is reversed 35 in going on to the heel, it is in active position where it will engage the leading needle l' of the series of long butt needles, and carry this needle down into the active plane. This long butt needle is utilized to actuate a 40 picker which is so constructed that when actuated by engagement with the long butt needle, it will lift the long butt needle and the suture needle s' at the rear end of the series of short butt needles up into the 45 inactive plane, so that this short butt needle will not knit during the first reverse stroke of the cam cylinder.

The picker for raising the suture needle s' from the active into the inactive series 50 during the first reverse stroke of the cylinder, is in the form of an arm 59 which is mounted to swing vertically about a pivot 60 carried by a pivot block 61. The block 61 is mounted to turn about a vertical pivot 62, so that the picker arm may move horizontally as well as vertically. The picker arm extends through a slot formed in the cam cylinder, and is provided on its inner 65 end with a needle engaging lip 63 adapted to underlie the path of the needle butts. The inner end of the picker is also provided 70 with a substantially vertical needle engaging shoulder 64, which is so arranged that it is out of the path of the short needle butts,

while in position to be engaged by the butt of a long butt needle. A spring 65 is connected to the picker, and tends to hold the picker in active position, as indicated in Figs. 4, 7 and 8 of the drawings. During the first reverse stroke of the cam cylinder 70 in passing on to the heel, the short butt needles pass idly by the picker 59 in a direction from right to left in Figs. 5, 7 and 8. As the rear end of the series of short butt needles approaches the picker 59, the 75 long butt needle l' is engaged by the depressing picker 18, and is brought down into the active series directly in advance of the short butt needles s' . When the long butt needle l' reaches the picker 59, it engages the 80 shoulder 64 of the picker and swings the picker toward the left in Figs. 7 and 8. At this time the horizontal lip 63 of the picker underlies the butt of the needle s' as well as the butt of the needle l' . During the 85 continued travel of the cam cylinder, the picker 59 will be swung toward the left by its engagement with the butt of the needle l' , and during this movement the picker arm rides up the incline 66, and also swings radially outward so that the needles l', s' are raised up out of the active series, and are delivered by the picker on to the upper end 90 of the elevating cam 31, by which their upward movement into the inactive series is 95 completed, the upper part of the cam 31 being of sufficient thickness to engage both long and short butt needles. Immediately the picker 59 is released from engagement with the needle butts, it is returned to normal position by the spring 65. When the picker 18 is operated by engagement with the butt of the needle l' , it is engaged by its latch 20 and is retained in inactive position during the narrowing operation. 100

The picker 59 is so arranged as described below that it is out of the path of the long butt needles during the knitting of the split foot, and is so mounted that it may ride idly along the butts of the long butt needles during rotary knitting. The construction and arrangement of the picker constitutes a feature of the invention which contributes to the simplicity of the construction and avoids the necessity of providing devices for throwing the picker into and out of active position at proper intervals. As shown, the picker 59 is so arranged that its inner end overlies the pivoted bridge-cam 67 which bridges over the space between the upper end of the elevating cam 10 and the upper surface of the stitch cam plate 7. With this arrangement of the picker, the long butt needles passing up the needle elevating cam 10, and on to the needle elevating cam 31, 115 will pass to the left of the picker, in Fig. 7, while the butts of the long butt needles 120 which pass down the needle depressing cam 125

33, and down the inclined end of the guard cam 35, will pass over and to the right of the picker. During rotary knitting the butts of the long butt needles strike the rear 5 (left Fig. 7) side of the inner end of the picker, and the spring 65 yields to allow the picker to swing toward the right and ride idly along the needle butts until the long butts have passed, when the picker is re- 10 turned by the spring to its normal position. When the long butt needles are raised into the inactive series at the beginning of the heel, the picker is therefore left in active position ready to operate in the manner 15 heretofore described.

The machine is provided with yarn changing mechanism 68 arranged to deliver yarn to the needles at the point where they are operated by the main knitting cams, and is 20 operated to change the yarn in passing from the leg to the heel and after the completion of the toe. The latch ring 69 is also provided with a thread guide 70 for feeding yarn to the needles at the point where they 25 are operated by the supplemental cams.

In order that the thread may be properly delivered to the needles during reciprocatory knitting in knitting the split foot, the thread guide 70 is made in the form of a circumferentially extending slot. The ends of the 30 guiding slot 70 are so arranged that they will act to properly direct the thread to the knitting waves formed by the knitting cams 7 and 8 respectively as the cam cylinder is reciprocated in knitting the split foot. In order to shift the thread from one end of the guiding slot to the other, and to insure the positioning of the thread against the end of the slot, thread guides 70^a and 70^b are 35 mounted on the sinker cam ring 70^c. These thread guiding devices on the sinker cam ring are so arranged with relation to each other and to the guiding slot 70, that during the rotation of the cam cylinder in one direction 40 the guiding device 70^b will engage the thread leading from the thread eye 69^a to the guiding slot 70, and will retain the thread in one end of the slot 70. When the motion of the cam cylinder is reversed, the sinker 45 cam ring shifts relatively to the cam cylinder and latch ring in the usual manner, and the thread guide 70^a engages the thread and carries it to the other end of the slot 70, and retains it in this end of the slot during 50 the movement of the cam cylinder in this direction. When the cam cylinder is again reversed, the thread guide 70^b engages the thread and carries it to the other end of the guiding slot 70 and retains it in this end of the slot during 55 the movement of the cam cylinder in this direction. The latch ring may be provided with a second thread guide 70^d similar to the guide 70, and arranged on the opposite side of the thread engaging devices 60

70^a and 70^b. With this construction the 65 thread guides 70^a and 70^b on the sinker cam ring will engage the thread between the two thread guides 70 and 70^b and deflect the thread so that it will run against the ends of the guiding slots 70 and 70^a, thus rendering the action of the thread guiding devices more certain and reliable. 70

Assuming that a split foot stocking is to be knit in which the leg and top of the foot are knit from black yarn, and the heel, toe 75 and bottom of the foot are to be knit from white yarn, the operation of the machine is as follows: During the knitting of the leg of the stocking the parts are in the position indicated in the drawings, and black yarn 80 is supplied to the needles by the yarn changing device, and also by the thread guide 70. Both the main and supplemental knitting cams act upon the needles, and two knitting waves are formed which follow each other 85 about the needles, so that at each rotation of the cam cylinder two courses of loops are knit, the cam cylinder rotating in the direction of the arrows, Figs. 7 and 9. When the heel is reached the clutch operating lever of 90 the machine is shifted to change the motion of the cam cylinder from rotary to reciprocatory. At this time the lever 56 is shifted to cause the shifting of the needle depressing cams 32 and 33 down into inactive position. 95 At the same time the cam arm 71 which holds the shifter ring 72 in normal position is operated to release the shifter ring. This shifter ring corresponds in construction to the shifter ring of the Mayo machine. 100 When the shifter ring is thus released, it is shifted by its spring 73 until the stop plate 74 engages the stop lever 75. This movement of the shifter ring brings the high part 76 of the cam plate 77 which is secured to the 105 ring into engagement with the cam post 21, swinging said post back so that the V-shaped cam at its upper end is out of the path of the pins 78 and 79 which project radially from the latches 19 and 20 for the depressing pickers. This movement of the shifter ring also moves the high part of the cam 110 80 out from engagement with the cam post 16 which controls the latches for the elevating pickers, allowing the cam post to 115 move forward into position to be engaged by the radially projecting pins on the picker latches. This throws the elevating pickers into operation. This movement of the shifter ring also shifts the cam arms 26, so that the 120 upper cam arm is moved out of active position, and the lower cam arm is moved into active position. During the continued advance movement of the cam cylinder after the shifter ring has been thus shifted, the 125 pin 27 rides against the cam surface on the lower cam arm 26, thus shifting the needle elevating cam 22, so that during the

last forward revolution of the cam cylinder, the long butt needles are raised into the upper or inactive plane. The rocking of the shaft 23 which moves the cam 22 into position to raise the long butt needles into the inactive plane also withdraws the switch cam 9 out of the path of the short butt needles and into position where it will operate upon the long butt needles when they are deflected down into the active plane. The yarn changing device is also operated at this time to change the yarn, so that white yarn is delivered to the needles at the point where they are operated on by the main knitting cams.

Since the long butt needles are raised into the inactive plane during the last forward movement of the needle cylinder before going on to the heel, the long butt needle l' will be the last needle to knit with the black yarn fed through the thread guide 70. During the formation of the heel the black thread leading through the thread guide 70 therefore draws idly back and forth through the thread guide as the cam cylinder reciprocates, being laid about the needles as the thread guide passes away from the needle l' in either direction, and being drawn back through the thread eye as the thread eye approaches the needle l' . The thread is held taut during this time by a takeup of the usual construction. The purpose of throwing the short butt suture needles s' up into the inactive series on the first return stroke of the needle cylinder in forming the heel can best be explained at this point. If the short butt needle s' were allowed to knit on the return stroke of the needle cylinder, the black thread leading from the needle l' to the thread guide 70 would lay across the needle s' at the time that this needle draws a loop of white yarn, and the black yarn would therefore be connected with the fabric at the needle s' . If this should occur, the black thread, instead of leading from the needle l' during the knitting of the heel, would lead from the needle s' , and when the knitting with the black thread upon the long butt needles was resumed in going from the heel on to the foot, the black thread would not be properly presented to the needle l' , and a stitch would be dropped at this point, thus forming a hole and imperfection in the fabric. During the first reverse stroke of the cam cylinder on the heel the suture needle s is raised into the inactive series by the picker 15, and the needle l' is carried down into the active plane by the picker 18, which is then latched in inactive position. The needles l' and s' are raised into the inactive series by the picker 59 in the manner already described. The short butt needle s^2 is therefore the last needle to knit with the white yarn during

this stroke of the needle cylinder, and the black yarn leads from the needle l' during the knitting of the heel, and is properly presented to the needle when this needle is operated during the formation of the first course on the foot. During the following reciprocations of the cam cylinder, the fabric knit by the short butt needles is narrowed by the pickers 14 and 15. When the narrowing has been completed, the stop lever 75 is operated to release the shifter ring 72, so that the ring is again shifted by its spring 73. This movement of the shifter ring carries the high part 76 of the cam 77 out of engagement with the cam post 21, so that the cam post moves forward into its most advanced position where the V-shaped cam at its upper end is in position to engage and operate both of the latch pins 78 and 79. This renders the depressing pickers active, so that the fabric which is knit upon the short butt needles is gradually widened. When the heel has been completed, the lever 56 is returned to the position indicated in Figs. 1 and 2, thus bringing the cam block 52 under the rod 50, and shifting the cam arm 46 into the position indicated in Fig. 1. This brings the cam arm into position to cause the shifting of the needle depressing cams 32 and 33 into their upper or active position. This movement of the lever 56 also shifts the shifter ring 72 back into its intermediate position, where the high part 76 of the cam plate 77 engages the cam post 21 and holds it back in its retracted position, thus throwing the depressing pickers out of operation. The connections through which this shifting of the shifter ring is effected, consists of an arm 81 secured to the rock shaft 54 and arranged to engage the end of the cam plate 77. When the shifter is moved back to its intermediate position by the arm 81 it is retained in this position by the stop lever 75 which drops down back of the stop plate 77. During the continued reciprocation of the cam cylinder, the short butt needles are actuated by the main knitting cams, while the long butt needles are actuated by the supplemental knitting cams, the short butt suture needle at the forward end of the series of short butt needles being lifted out of the active plane at each stroke of the cam cylinder, so that only that short butt needle which is the last to knit in the series of short butt needles is actuated at each stroke of the cam cylinder.

When the foot has been completed and the toe is reached, the lever 56 is again operated to shift the cam block 52 to swing the cam arm 46 into position where it will operate to move the needle depressing cams 32 and 33 into inactive position. The long butt needles will now remain in the upper inactive series, and the fabric knit upon

the short butt needles will be gradually narrowed by the action of the elevating pickers. When the narrowing is completed, the stop lever 75 will be again operated to release the shifter ring 72, so that it may be shifted into its extreme position, thus throwing the needle depressing pickers into operation to effect the widening. After the widening has been completed, the motion 10 changing clutch will be shifted to change the motion from reciprocating to rotary, and the cam lever 71 will be operated to return the shifter ring 72 to its initial position. This movement of the shifter ring 15 will operate the cam arm 26 to move the lower arm out of active position to bring the upper arm into active position, and will also carry the cam plate 77 into position where the cam post 21 will rest against the 20 intermediate portion 82 of the cam plate. At this time also the lever 56 is shifted to throw the cam arm 46 into position to operate the needle-depressing cams 32 and raise them into their active position. Now during 25 the first revolution of the cam cylinder on rotary knitting, the rack slide 25 will be depressed, thus rocking the shaft 23 and throwing the cam 22 up out of active position, and bring the cam lip 22' into position 30 to direct all the needles in the upper or inactive series down into the active or lower plane. This movement of the rock shaft 23 also moves the switch cam 9 radially inward into position to be engaged by the butts of 35 the short butt needles. During this revolution of the cam cylinder the pin 45 rides against the cam 46, thus shifting the needle depressing cams 32 and 33 into their upper or active position. The movement of the 40 needle depressing cams 32 at this time effects no function, and is due to the fact that in the Mayo machine the lever 56 is shifted at this time. During this revolution of the cam cylinder, also, the latch pin 79, which 45 is somewhat longer than the latch pin 78, rides over the cam at the upper end of the cam post 21, thus releasing the depressing picker 18, so that this picker remains in active position during rotary knitting, ready 50 to depress a long butt needle 'l' during the first reverse stroke in going on to the heel, as above described. The inner end of the cam at the upper end of the cam post 21 may be cut away, as indicated in Fig. 11, so that it 55 will give the latch 20 just enough movement to release the picker 18. This will reduce the weight on the cam post as the latch pin rapidly passes over the post during rotary knitting. As the change is 60 made from reciprocating to rotary knitting after the completion of the toe, the yarn changer is operated to change the yarn so that black yarn will be delivered to the

needles during rotary knitting. The parts remain in this position until the next heel 65 is reached, when the cycle of operations described is repeated.

While I prefer to employ the specific construction and arrangement of the parts shown and described in embodying the invention in a machine similar to the Mayo machine and to the machine of the application above referred to, it will be understood that this specific construction and arrangement of parts is not essential to the invention in its broader aspects, and may be varied and modified in accordance with the construction and arrangement of the various devices in the particular machine in which the invention is to be embodied, without departing from the invention.

Having set forth the nature and object of the invention, and specifically described one form of machine in which it may be embodied, what I claim is:

1. A circular knitting machine, having, in combination, a needle cylinder provided with long and short butt needles, a cam cylinder provided with main knitting cams, supplemental knitting cams arranged to act 90 upon only the long butt needles during reciprocatory knitting, needle elevating cams arranged on opposite sides of the supplemental cams in a position to engage the long butt needles only, vertically movable 95 needle depressing cams, a rock shaft carried with the cam cylinder connections to raise and lower the needle depressing cams from the rock shaft, and a stationary cam arm and connections for operating the rock 100 shaft, substantially as described.

2. A circular knitting machine, having, in combination, a needle cylinder provided with long and short butt needles, a cam cylinder provided with main knitting cams, 105 supplemental knitting cams arranged to act upon only the long butt needles during reciprocatory knitting, needle elevating cams arranged on opposite sides of the supplemental knitting cams in position to engage 110 the long butt needles only, needle depressing cams arranged on opposite sides of the supplemental knitting cams, a relatively stationary cam arm, and devices on the cam cylinder arranged to be operated by engagement with the cam arm for simultaneously raising and lowering the needle depressing cams, substantially as described.

3. A circular knitting machine, having, in combination, a needle cylinder provided 120 with long and short butt needles, a cam cylinder provided with main knitting cams, supplemental knitting cams arranged to act upon only the long butt needles during reciprocatory knitting, needle depressing 125 cams on opposite sides of the supplemental

knitting cams for directing the long butt needles into the supplemental knitting cams, a relatively stationary cam arm, devices on the cam cylinder connected with 5 the needle depressing cams arranged to engage and to be operated by the cam arm, and means for shifting the cam arm alternately into position to render the needle depressing cams active and inactive, substantially as described.

4. A circular knitting machine, having, in combination, a cam cylinder provided with needle depressing cams 32 and 33, devices for raising and lowering the needle engaging cams provided with a projecting pin 45, a relatively stationary cam arm 46, and means for shifting the cam arm to move the pin 45 alternately in opposite directions to render the cams 32 and 33 active and inactive, substantially as described.

5. A circular knitting machine, having, in combination, a needle cylinder provided with long and short butt needles, means for raising the long butt needles into the inactive plane, means for shifting one of the long butt needles into the active plane, and means operated by said needle for shifting said needle and an adjacent short butt needle into the inactive plane, substantially as described.

6. A circular knitting machine, having, in combination, a needle cylinder, needles therein comprising two substantially semicircular groups, suture needles interposed between the needles at the ends of one group, cams for operating each group of needles, narrowing and widening devices, devices for rendering one group of needles inactive during the narrowing and widening, means for 40 transferring one of the inactive needles to the active series during the knitting of the first course of reciprocatory knitting, and means operated by this needle for transferring said needle and the suture needle which is the 45 last in its group to the inactive series during the knitting of said course, substantially as described.

7. A circular knitting machine, having, in combination, a needle cylinder, needles therein comprising two substantially semicircular groups, suture needles interposed between the needles at the ends of one group, cams for operating each group of needles, needle elevating and needle depressing pickers for 55 effecting the narrowing and widening, devices for rendering one group of needles inactive during the narrowing and widening, means for rendering one of the widening pickers active during the first reverse stroke 60 of reciprocatory knitting, and a picker arranged to be operated by the needle depressed by said needle depressing picker and to transfer said needle and that suture needle which is the last in its group to the inactive

series during said stroke, substantially as described.

8. A circular knitting machine, having, in combination, a needle cylinder, needles therein comprising two substantially semicircular groups of long and short butt needles, short butt suture needles interposed between the needles at the ends of the group of long butt needles, knitting cams for operating each group of needles, needle elevating and needle depressing pickers for effecting the narrowing and widening, devices for raising the long butt needles into the inactive plane during the narrowing and widening, means for rendering one of the needle depressing pickers active during the first 75 reverse stroke of reciprocatory knitting, and a needle elevating picker for raising the needle depressed by said needle depressing picker and the adjacent short butt suture needle to the inactive series during said stroke, substantially as described.

9. A circular knitting machine, having, in combination, a needle cylinder provided with long and short butt needles, short butt suture needles between the needles at the ends of the series of long butt needles, main knitting cams, supplemental knitting cams, means for causing the supplemental cams to act upon only the long butt needles during reciprocatory knitting, means for transferring a long butt needle to the active series during the first reverse stroke of reciprocatory knitting, and a needle elevating picker arranged to raise said needle and the adjacent short butt suture needle into the inactive series and arranged out of the path of the long butt needles passing through the supplemental knitting cams during reciprocatory knitting, substantially as described.

10. A circular knitting machine, having, in combination, a needle cylinder, needles therein comprising two substantially semicircular groups, suture needles interposed between the needles at the end of one group, cams for operating each group of needles, means for rendering one group of needles inactive during the narrowing and widening, and a picker, means for causing the picker to act on the suture needle at the rear end of its group during the first course of reciprocatory knitting mounted to ride along the needles during rotary knitting and arranged out of the path of the needles during reciprocatory knitting, substantially as described.

11. A circular knitting machine, having, in combination, a needle cylinder provided with long and short butt needles, a picker having a needle shifting lip adapted to operate on the butts of two adjacent needles, and a shoulder arranged out of the path of passing short butts and to be engaged by a passing long butt, substantially as described.

12. A circular knitting machine, having, in combination, a needle cylinder provided with long and short butt needles, a picker having a needle shifting lip adapted to operate on the butts of two adjacent needles, and a shoulder arranged out of the path of passing short butts and to be engaged by a passing long butt, and means for shifting a long butt needle into position to act upon and

to be acted upon by said picker, substantially as described.

In testimony whereof I affix my signature, in presence of two witnesses.

EXILIAS PAQUETTE.
